US0D1072806S

(12) **United States Design Patent** (10) Patent No.: **US D1,072,806 S**
 Chien et al. (45) Date of Patent: ** Apr. 29, 2025

(54) **NOTEBOOK COMPUTER**

(71) Applicants: **Po-Yang Chien**, Taipei (TW); **Hao-Jen Fang**, Taipei (TW); **Wei-Yi Chang**, Taipei (TW); **Chun-Chieh Chen**, Taipei (TW); **Chen-Cheng Wang**, Taipei (TW); **Chih-Wen Chiang**, Taipei (TW); **Sheng-Hung Lee**, Taipei (TW)

(72) Inventors: **Po-Yang Chien**, Taipei (TW); **Hao-Jen Fang**, Taipei (TW); **Wei-Yi Chang**, Taipei (TW); **Chun-Chieh Chen**, Taipei (TW); **Chen-Cheng Wang**, Taipei (TW); **Chih-Wen Chiang**, Taipei (TW); **Sheng-Hung Lee**, Taipei (TW)

(73) Assignee: **COMPAL ELECTRONICS, INC.**,
Taipei (TW)

(**) Term: **15 Years**

(21) Appl. No.: **29/767,597**

(22) Filed: **Jan. 24, 2021**

(30) **Foreign Application Priority Data**

Nov. 6, 2020 (TW) 109306166

(51) LOC (15) Cl. **14-02**

(52) U.S. Cl.

USPC **D14/315**; D14/327

(58) **Field of Classification Search**

USPC D14/127, 130, 203.4, 306, 310–312, D14/315–316, 318, 320, 323, 327, 331, D14/337, 341, 345–346, 357, 367, 371, D14/373–374, 376, 439–440, 487, 495, D14/448; D24/160, 185–186; D21/324, D21/329–332, 369, 515; D10/70–72, D10/104.1, 106.1, 106.95, 108–109.2

CPC G06F 1/1641; G06F 1/1652; G06F 1/1618; G06F 1/1649; G06F 1/1616; G06F 1/1637; F21S 8/00

(57) **CLAIM**

The ornamental design for a notebook computer as shown and described.

DESCRIPTION

FIG. 1 is a perspective view of a notebook computer showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a notebook computer showing a second embodiment of our new design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a notebook computer showing a third embodiment of our new design;

FIG. 16 is a front view thereof;

FIG. 17 is a rear view thereof;

FIG. 18 is a left side view thereof;

FIG. 19 is a right side view thereof;

FIG. 20 is a top view thereof; and,

FIG. 21 is a bottom view thereof.

The even-dash broken lines illustrate portions of the notebook computer that form no part of the claimed design. The dot-dash broken lines define the bounds of the claimed design and form no part thereof.
